CLAIM

The ornamental design for a bowl, as shown and described.

DESCRIPTION

FIG. 1 is a general perspective view of a first embodiment of a bowl embodying the present invention;

FIG. 2 is a front elevational view of the bowl shown in FIG. 1, the side and rear elevational views appearing identical;

FIG. 3 is a top plan view of the bowl shown in FIG. 1; FIG. 4 is a bottom plan view of the bowl shown in FIG. 1;

FIG. 5 is a general perspective view of a bowl which is an alternative embodiment of the present invention, differing from the bowl shown in FIG. 1 only dimensionally;

FIG. 6 is a front elevational view of the bowl shown in FIG. 5, the side and rear elevational views appearing identical;

FIG. 7 is a top plan view of the bowl shown in FIG. 5; and,

FIG. 8 is a bottom plan view of the bowl shown in FIG. 5.
